UNITED STATES PATENT OFFICE.

WILLIAM A. CROSS, OF CHICAGO, ILLINOIS.

AUTOMATIC DOOR-CLOSING MECHANISM.

SPECIFICATION forming part of Letters Patent No. 727,097, dated May 5, 1903.

Application filed June 20, 1902. Serial No. 112,407. (No model.)

To all whom it may concern:

Be it known that I, WILLIAM A. CROSS, a citizen of the United States of America, and a resident of Chicago, in the county of Cook and State of Illinois, have invented certain new and useful Improvements in Automatic Door-Closing Mechanism, of which the following is a specification.

The present invention relates to an automatic mechanism for closing the well-doors of elevators, and has for its object to provide a simple and efficient automatic operating mechanism that with the elevator cage or platform reaching a proper floor or level will automatically cause an opening of the well-doors at such floor or level and with a departure of the cage or platform from such floor or level will automatically cause such doors to return to a closed position, all as will hereinafter more fully appear and be more particularly pointed out in the claims.

In the accompanying drawings, illustrative of the present invention, Figure 1 is a vertical sectional elevation of an elevator-well, illustrating the application of the present invention to the vertically-moving doors by which the tier of openings into the well are closed, parts being broken away to better illustrate the arrangement of the present invention; Fig. 2, a diagrammatic view illustrating the electrically-actuated mechanism of the present invention.

Similar numerals of reference indicate like parts in both views.

Referring to the drawings, 1 represents the usual elevator-well, in which doorways are formed at the different floors of the building, and 2 the elevator cage or platform, arranged to move vertically in such well in any usual manner.

3 and 4 are the respective upper and lower sections or halves of the series of doors which normally close the series of doorways or openings of the elevator-well. Such halves or sections are operatively connected together, so as to simultaneously move in opposite directions in the operation of opening or closing a particular doorway or opening in the elevator-well. The connection imposing such simultaneous movement upon the door-sections in opposite directions will consist of the usual

chain and pulley connections 5 and 6, an example of which may be found in my prior patent of May 19, 1896, No. 560,396. Such special type of door is, however, merely used 55 to illustrate the present invention, and any other usual and suitable type of door may be employed in connection with the present invention where circumstances or the judgment of the constructor may so indicate. 60

In the special type of apparatus shown in the drawings, 7 is a horizontally-arranged endless chain belt moving in unison with the chain and pulley connections 5 and 6 of the doors and provided with an operating finger 65 or lug 8, which in the movement of the endless chain 7 in unison with the movement of the door-sections is adapted to have a reciprocating movement in a horizontal plane for automatically operating the cut-out switches, 70 as hereinafter more fully described.

9 is a reversible electric motor of any usual type, the armature-shaft of which is provided with a pulley 10, that is connected by a chain or other flexible belt 11 with a pulley 12, secured to the carrying-shaft of one of the pulleys 6, heretofore described, the arrangement being such that the motor is adapted to impart positive opening and closing movements to the door-sections in the automatic manner 8c hereinafter described.

13 is a pole-changer of any usual and suitable construction, secured to the wall of the elevator-well, with its movable arms 14 arranged to project into the path of an operating cam-plate 15, carried by the elevator cab or platform 2, the arrangement being such that with the elevator cab or platform on the proper level with the particular floor of the building the cam-plate 15 will be in active 90 engagement with the movable arm 14 to hold the same in a reversed position and with the current directed to the motor, so that the same will tend to operate the door-sections into an open position. 95

16 is a spring tending to hold the movable arm 14 in a position the reverse to that already described and with the current directed to the motor, so that the same will tend to operate the door-sections into a closed position. The last-described condition is the normal one of the various pole-changers employed 100

and is only changed when the elevator cab or platform reaches the proper proximity to a particular pole-changer.

The connections and circuits between the source of electrical power, the pole-changer, motor, &c., are usual and common to reversible motors, and, in connection with diagram view Fig. 2, will be clearly understood by those skilled in the art.

10 17 and 18 are a pair of circuit breakers or switches located between a pole-changer 13 and motor 9 and arranged in the path of the reciprocating operating-finger 8, heretofore described, and near the respective terminals 15 of such path, so that as said operating-finger nears the terminal of its movement in either direction, and which terminal or final movements of the said finger are coincident with the final closing and opening movements of 20 the door-sections, the said finger will break or interrupt the active circuit of the motor to prevent further rotation of the same.

Having thus fully described my said invention, what I claim as new, and desire to secure 25 by Letters Patent, is—

1. In an automatic operating mechanism for elevator hatchway-doors, the combination of a sliding door formed in two sections, an intermediate connection imposing simultaneous movement on such door-sections to and from each other, an electric motor operatively connected with and adapted to open and close the door-sections, a pole-changer in circuit with said motor, an elevator cab or platform, 30 a projection carried by said cab and adapted to operate the pole-changer in a passage past the same, a normally closed circuit-breaker in circuit with the electric motor, and means moving in unison with the door-sections for 35 opening said circuit-breaker as said door-sections reach their closed position, substantially as set forth.

2. In an automatic operating mechanism for elevator hatchway-doors, the combination 45 of a sliding door formed in two sections, an intermediate connection imposing simultaneous movement on such door-sections to and from each other, an electric motor operatively connected with and adapted to open and close the door-sections, a pole-changer in circuit with said motor, an elevator cab or platform, 50 a projection carried by said cab and adapted to operate the pole-changer in a passage past the same, a pair of independent normally closed circuit-breakers in circuit with the electric motor, and means moving in unison with the door-sections for alternately opening 55 said circuit-breakers as the door-sections alternately reach their closed and open positions, substantially as set forth.

3. In an automatic operating mechanism for elevator hatchway-doors, the combination 60 of a sliding door formed in two sections, an intermediate connection imposing simultaneous movement on such door-sections to and from each other, an electric motor operatively connected with said intermediate connection

and adapted to open and close the door-sections, a pole-changer in circuit with said motor, an elevator cab or platform, a projection 70 carried by said cab and adapted to operate the pole-changer in a passage past the same, a normally closed circuit-breaker in circuit with the electric motor, and means moving in unison with the door-sections for opening said 75 circuit-breaker as said sections reach their closed position, substantially as set forth.

4. In an automatic operating mechanism for elevator hatchway-doors, the combination of a sliding door formed in two sections, an intermediate connection imposing simultaneous movement on such door-sections to and from each other, an electric motor operatively connected with said intermediate connection and adapted to open and close the door-sections, a pole-changer in circuit with said motor, an elevator cab or platform, a projection 80 carried by said cab and adapted to operate the pole-changer in a passage past the same, a pair of independent normally closed circuit-breakers in circuit with the electric motor, and means moving in unison with the door-sections for alternately opening said circuit-breakers as the door-sections alternately 85 reach their closed and opened positions, substantially as set forth.

5. In an automatic operating mechanism for elevator hatchway-doors, the combination of a sliding door formed in two sections, an intermediate connection imposing simultaneous movement on such door-sections to and from each other, an electric motor operatively connected with and adapted to open and close the door-sections, a pole-changer in circuit with said motor, means for yieldingly holding 90 said pole-changer in one position, an elevator cab or platform, a projection carried by said cab and adapted to reverse the position of such pole-changer by engagement therewith in the passage of the elevator-cab, a normally closed circuit-breaker in circuit with the electric motor, and means moving in unison with the door-sections for opening said circuit-breaker as said door-sections reach their 95 closed position, substantially as set forth.

6. In an automatic operating mechanism for elevator hatchway-doors, the combination of a sliding door formed in two sections, an intermediate connection imposing simultaneous movement on such door-sections to and from each other, an electric motor operatively connected with and adapted to open and close the door-sections, a pole-changer in circuit with said motor, means for yieldingly holding 100 said pole-changer in one position, an elevator cab or platform, a projection carried by said cab and adapted to reverse the position of such pole-changer by engagement therewith in the passage of the elevator-cab, a normally closed circuit-breaker in circuit with the electric motor, and means moving in unison with the door-sections for opening said circuit-breaker as said door-sections reach their 105 closed position, substantially as set forth.

7. In an automatic operating mechanism for elevator hatchway-doors, the combination of a sliding door formed in two sections, an intermediate connection imposing simultaneous movement on such door-sections to and from each other, an electric motor operatively connected with and adapted to open and close the door-sections, a pole-changer in circuit with said motor, means for yieldingly holding 110 said pole-changer in one position, an elevator cab or platform, a projection carried by said cab and adapted to reverse the position of such pole-changer by engagement therewith in the passage of the elevator-cab, a pair of independent normally closed circuit-breakers in circuit with the electric motor, and means moving in unison with the door-sections for alternately opening said circuit-breakers as the door-sections alternately 115

8. In an automatic operating mechanism for elevator hatchway-doors, the combination of a sliding door formed in two sections, an intermediate connection imposing simultaneous movement on such door-sections to and from each other, an electric motor operatively connected with said intermediate connection and adapted to open and close the door-sections, a pole-changer in circuit with said motor, means for yieldingly holding 120 said pole-changer in one position, an elevator cab or platform, a projection carried by said cab and adapted to reverse the position of such pole-changer by engagement therewith in the passage of the elevator-cab, a pair of independent normally closed circuit-breakers in circuit with the electric motor, and means moving in unison with the door-sections for alternately opening said circuit-breakers as the door-sections alternately 125

9. In an automatic operating mechanism for elevator hatchway-doors, the combination of a sliding door formed in two sections, an intermediate connection imposing simultaneous movement on such door-sections to and from each other, an electric motor operatively connected with said intermediate connection and adapted to open and close the door-sections, a pole-changer in circuit with said motor, means for yieldingly holding 130 said pole-changer in one position, an elevator cab or platform, a projection carried by said cab and adapted to reverse the position of such pole-changer by engagement therewith in the passage of the elevator-cab, a pair of independent normally closed circuit-breakers in circuit with the electric motor, and means moving in unison with the door-sections for alternately opening said circuit-breakers as the door-sections alternately

reach their closed and opened positions, substantially as set forth.

7. In an automatic operating mechanism for elevator hatchway-doors, the combination of a sliding door formed in two sections, a pair of pulley and flexible connections imposing simultaneous movement on such door-sections to and from each other, an endless flexible connection extending from one pulley to the other, an electric motor operatively connected with one of said pulleys and adapted to open and close the door-sections, a pole-changer in circuit with said motor, an elevator cab or platform, a projection carried by said cab and adapted to operate the pole-changer in a passage past the same, a pair of independent normally closed circuit-breakers in circuit with the electric motor, and means carried by the endless connection aforesaid for alternately opening said circuit-breakers as the door-sections alternately reach their closed and opened positions, substantially as set forth.

8. In an automatic operating mechanism for elevator hatchway-doors, the combination of a sliding door formed in two sections, a pair

of pulley and flexible connections imposing simultaneous movement on such door-sections to and from each other, an endless flexible connection extending from one pulley to the other, an electric motor operatively connected with one of said pulleys and adapted to open and close the door-sections, a pole-changer in circuit with said motor, an elevator cab or platform, a projection carried by said cab and adapted to operate the pole-changer in a passage past the same, a pair of independent normally closed circuit-breakers in circuit with the electric motor, and means carried by the endless connection aforesaid for alternately opening said circuit-breakers as the door-sections alternately reach their closed and opened positions, substantially as set forth.

Signed at Chicago, Illinois, this 14th day of June, 1902.

WILLIAM A. CROSS.
